HANGER FOR TROLLEY RAILS

Burtis B. McCarn, Jersey City, N. J.

Application October 19, 1944, Serial No. 559,340

7 Claims. (Cl. 104—111)

1

This invention relates to improvements in hangers for load bearing trolley rails and more particularly to hangers for use between a standardized hard steel rail and a superstructure above it. In common practice, such a rail spans the distance between hangers and the superstructure spans a larger distance between overhead supports.

An object of the invention is to provide a hanger that may be manufactured by quantity production methods for stock, such that it is adaptable for a wide variety of uses with the standardized trolley rail for which the hanger is made. Another object is to provide a hanger of greater strength than those in general use, particularly of greater strength to resist the side thrust due to moving loads or off-side hoisting. Another object is to provide a hanger especially useful for resisting stresses due to a tractor drive applied to the trolley rail, while at the same time providing simple means to support electrical conductors for the said tractor drive and for hoisting.

Other objects will be in part obvious from the annexed drawings and in part hereinafter indicated in connection therewith by the following analysis of the invention.

In the drawings:

Fig. 1 is an elevation of one hanger according to the invention in the position of use between a particular trolley rail of common type and a two-channel superstructure of common type.

Fig. 2 is a section taken along line 2—2 of Fig. 1.

Fig. 3 is a section similar to Fig. 2, in which the superstructure consists of two structural channels attached together so as to form a T section.

Fig. 4 is a section similar to Fig. 2, in which the superstructure is an I beam.

Fig. 5 is an elevation like Fig. 1 except that provision for the support of insulators that may carry electrical conductors, has been incorporated in the hanger.

Fig. 6 is an enlarged diagram showing the profile of the shallow thread for a jam nut of Figs. 1, 2 and 5, compared with the profile of a fully formed thread for a standard nut.

Fig. 7A and Fig. 7B taken together show an enlarged section taken through the center line of one arm 12 of Fig. 1 and looking in the direction of the other arm 12, and using the same numerals used in Fig. 1, except that an extra washer 17 is shown between the channels 20, 20 and the nut 19. The said extra washer may be used or omitted, per common practice.

2

Referring to the drawings, wherein like reference characters indicate like parts throughout the several views, 10 indicates generally a hanger according to the invention. Figs. 1 and 2 show hanger 10 as used with a particular standardized hard steel rail, the cross section of which comprises two equal parts 21, 21 clamped to the hanger per common practice, and as used with a common double channel superstructure made of channels 20, 20. Hanger 10 is formed to have a body portion 11 and two arms 12, 12 perpendicular to it. For use with the rail sections 21, 21 the body portion 11 will have a shear lug 13 on each side as commonly designed for hangers to fit such rail sections. For use with any other kind of standardized monorail, the body portion will have means for attachment to the said monorail as commonly designed for hangers to fit such a monorail. As an old element in my combination, I claim any common or known means for attachment to a standardized hard steel rail, of the hanger. Each arm 12 has at its free end a standard screw thread 15. 16 is a standard nut. 17 is a standard washer as commonly used with such superstructure. Continuing from thread 15, is thread 18 having the same pitch and the same number of threads per inch, but having substantially less depth to the root of the thread than 15. 19 is a jam nut tapped to fit thread 18. 20 A jam nut is a nut designed to operate, for thread-lock purposes, upon the principle of jamming or wedging the thread of the nut against the coacting thread of the screw. The threads described are such that the jam nut will turn past thread 15 and into its position of use.

The combination of a rod with two kinds of thread related as described above and with two kinds of nuts as described above, is claimed in my copending application, Serial Number 702,771, filed October 11, 1946, for an Improvement in Adjustable Clamping and Locking Means.

The hanger 10 is preferably made from a length of round rolled steel bar, the mid section of which is heated for bending and forging to form the body portion 11, and while in the heated condition, it may be compressed longitudinally to upset the bar to provide sufficient metal for the ample height and width indicated for 11 (Fig. 1), the said width being such that the body portion has end projections 14, 14 outside the two arms, the ample height and width being desirable to increase the strength of the hanger and to increase the amount of support of the rail sections by the hanger.

If the hanger of Fig. 1 had fully formed threads

at 18, 18 and if it were cut through the body portion 11 to make two equal halves, one of the halves would be similar to a common single shank hanger of the prior art and would employ a minimum of material for the use shown. However, for a general purpose hanger to be carried in stock, it is desirable to have a greater length for the shear bars 13, 13. The U shaped hanger of Fig. 1 can be formed very economically from a single length of rolled steel rod by common means, to provide ample length for the shear lugs. After being so made, the U shaped hanger is found to possess a distinct advantage over common single-shank hangers made from the same size of rod. It has been found from the use of various common forms of hangers that the hangers partially integrate the rail with the superstructure due to clamping effects as from the superstructure channels clamped against hangers, hangers clamped to superstructure and rail sections clamped to hangers. This is advantageous for reducing deflection at the rail, but it subjects the hangers to additional stresses so as to require stronger bars or hangers. The hangers tend to bend just below the superstructure, in a direction lengthwise of the rail. To resist deflection at the rail the U shaped hanger of Fig. 1 with shanks spaced apart five diameters of the rod has a section modulus just below the superstructure, thirty three and two thirds times the section modulus of a single-shank hanger made from the same size of rod, the greater strength being secured generally without the use of any more metal. If the U shaped hanger is in a position where it tends to fail laterally in addition to longitudinally, it will not be so much stronger than a single-shank hanger made from the same size of rod, but it will always be at least twice as strong.

Fig. 3 shows hanger 22 like 10 except that the two arms 23 have no partially formed thread and are provided with standard jam nuts 24. The superstructure consists of two channels 25 and 26 set to form a T section. The plurality of hangers 22, when installed in their positions of use, may hold or assist in holding channels 25 and 26 together to form the T section.

Fig. 4 shows a hanger 27 which may be the same as hanger 22 except that the two arms 23, 23 are bent or sprung to attach to an I beam 28 punched on standard gauge lines. An I beam is a common form of superstructure, so it is desirable that a hanger of general utility be adaptable for use with it.

Fig. 5 shows a hanger 29 like 10 except that a bar or plate 30 is welded in position between the arms 12, 12. Plate 30 has a hole 31 for attachment of supporting insulators for electrical conductors and is attached to the arms by fillet welds 32, 32. Plate 30 increases the strength of the hanger in a direction lengthwise of the rail. Single-shank hangers have been found unsatisfactory for the support of such insulators when a traction drive is used against the rail because the resulting stresses spring the hangers and crack the insulators, and various supplementary devices have been used to prevent this. It is obvious that hanger 29 will resist such springing without the use of any extra material. The use of a punched plate for supporting insulators, in combination with a U shaped hanger, is a substantial improvement.

Fig. 6 illustrates a profile 78 for a partially formed thread 18 compared with a profile 75 for a fully formed thread 15 to show how thread 18

may provide a rounded form at the root and also leave a greater sectional area of rod at root of thread, each feature providing a stronger hanger at the critical section just below the jam nut, as compared with corresponding features of a fully formed thread. The partially formed thread can be made more economically than a fully formed thread.

The combination of a portion of a rod, a screw thread having the profile of the shallow thread with a rounded form at the root as shown in Fig. 6, and a nut to fit the screw thread, is claimed in my copending application, Serial No. 170,221, filed June 24, 1950, for an improvement in Threaded Fastenings.

As many changes could be made in carrying out the above constructions without departing from the scope of the invention, it is intended that all matter contained in the above description or shown in the accompanying drawings shall be interpreted as illustrative and not in a limiting sense.

I claim:

1. A hanger for a standardized trolley rail having two continuous shear lugs as elements of the rail head, comprising: a body portion having two shear lugs of length substantially equal to the length of the hanger, the said length being measured along the rail as the hanger is in its position of use; two arms perpendicular to the body portion, spaced apart and integrally joined by the body portion, each arm extending upward from the body portion and having at its free extremity a thread of length greater than the thickness of a standard nut for the said thread, and continuing therefrom an additional amount of thread of length greater than the thickness of a jam nut therefor; two standard nuts tapped to fit the two arms respectively, and two jam nuts tapped to fit the two arms respectively; and a rectangular plate having provision for attachment of electrical conductors, the two ends of the plate being welded to the two arms respectively above the junction of the arm with the body portion of the hanger and below the threaded portion of the arm.

2. A hanger for adjustably suspending a trolley rail from a supporting structure and for supporting and maintaining the said rail in its suspended position, comprising: a unitary structure consisting of a body portion having means for ready attachment to and for the support of said rail, and additionally consisting of two elongated upstanding arms integrally formed at their lower ends with the said body portion and spaced from each other longitudinally of the main body portion and of said rail, with said arms of such length as to space the body portion of the hanger and the trolley rail a substantial distance below the supporting structure; and clamping means at the end of each arm, each of the said clamping means consisting of a threaded fastening having at least one nut suitable for use as a load-bearing nut and at least one nut suitable for use as a jam nut.

3. A hanger according to claim 2, characterized by the further facts that the said body portion has a length greater than its depth, and that each of the said arms has a diameter substantially equal to one-fifth of the distance that the arms are spaced from each other.

4. A hanger for use for adjustably suspending from a superstructure and for supporting and maintaining in the suspended position, a stand-

ardized trolley rail having two continuous shear lugs as elements of the rail head, comprising: a unitary structure consisting of a body portion having two shear lugs extending longitudinally across the two sides respectively thereof and adapted to engage the continuous shear lugs of the rail head, and additionally consisting of two elongated upstanding arms perpendicular to the said two shear lugs, integrally formed at their lower ends with the said body portion and spaced from each other longitudinally of the main body portion and of said rail, with said arms of such length as to space the body portion of the hanger and the trolley rail a substantial distance below the supporting structure; and clamping means at the end of each arm, each of the said clamping means consisting of a threaded fastening having at least one nut suitable for use as a load-bearing nut and at least one nut suitable for use as a jam nut.

5. A hanger according to claim 4, characterized by the further facts that the said body portion has a length greater than its depth, and that each of the said arms has a diameter substantially equal to one-fifth of the distance that the 25 arms are spaced from each other.

6. A hanger for adjustably suspending a trolley rail from a supporting structure and for supporting and maintaining the said rail in its suspended position, comprising: a unitary structure 30 having two elongated upstanding arms integral- 35 ly fastened together at their lower ends and spaced from each other longitudinally of the rail, said arms being of such length as to space the trolley rail a substantial distance below the sup- porting structure, and clamping means at the free end of each arm, each of the said clamping means consisting of a threaded fastening hav- 40 ing at least one nut suitable for use as a load- bearing nut and at least one nut suitable for use as a jam nut.

7. A hanger according to claim 2, characterized

by the further facts that the said hanger also includes a rectangular plate having provision for the attachment of electrical conductors thereto, the two ends of the plate being welded to the two arms respectively of the unitary structure, above the body portion of the unitary structure and below the clamping means of each arm.
